UNITED STATES PATENT OFFICE.

ISAAC W. HEYSINGER, OF PHILADELPHIA, PENNSYLVANIA.

SELF-CLOSING COVER FOR INKSTANDS, &c.

SPECIFICATION forming part of Letters Patent No. 404,539, dated June 4, 1889.

Application filed June 16, 1888. Serial No. 277,329. (No model.)

To all whom it may concern:

Be it known that I, ISAAC W. HEYSINGER, of Philadelphia, in the county of Philadelphia and State of Pennsylvania, have invented a certain new and useful Improvement in Self-Closing Covers for Inkstands, &c., of which the following is a full, clear, and exact description, reference being had to the drawings accompanying and which form a part of this specification, in which—

Figure 1 is a vertical section, from front to rear, through an inkstand-cover and ink-well embodying my invention. Fig. 2 is a top view of a horizontal section along the dotted line $x x$ of Fig. 1. Fig. 3 is a transverse vertical section through the self-closing cover, as shown in the dotted lines $y y$ of Fig. 1. Fig. 4 is a vertical section through the valve and its supporting-tube. Fig. 5 shows the means of attaching the slotted metal tube to the top of the glass valve. Fig. 6 is an end and 6^a a side view of the slotted tube, showing the spring-finger which engages with a notch upon the face of the valve. Fig. 7 is a modification of Fig. 1, in which the ink-well and cover are square in cross-section, and in which the shoulder upon which the cover rests is provided with an internal instead of external lip or flange. Fig. 8 is a horizontal section along the dotted line $x x$ of Fig. 7. Fig. 9 shows the supports of the valve when the split or slotted tube is prolonged, as shown in Fig. 5, and the ends thereof serve as pins to support the valve in bearings in the hood or cover. Fig. 10 shows my invention as a self-feeding inkstand, in which the ink-well is supplied with ink from a lateral reservoir through an orifice at the bottom, forming a communicating passage between the lower parts of the ink-well and the pneumatic reservoir, as air gradually finds its way from the ink-well, as the level is reduced below the upper margin of the passage in said ink-well, the same being provided with my self-closing cover, adapted to give access thereto, and supplying ink to pens from a surface at a fixed height relatively to said cover; and Fig. 11 shows my hood or cover elongated from side to side and provided with multiple valves, each opening into a separate ink-well in the base.

The lettering in all the figures is uniform. My invention relates to an inkstand-cover

and inkstand or the like for use upon desks, &c., in which cover is supported a rearwardly swinging valve pivoted above and closing 55 against lateral flanges, said cover open in front to give access to said valve, which closes automatically when the pressure of a pen is removed therefrom; and my present invention is an improvement upon the patented 6c inkstand for which I received Letters Patent of the United States No. 307,764, and bearing date November 11, 1884.

The improvements which form the subject-matter of my present invention consist in 65 making my inkstand of glass and providing the same with an ink-well having a raised lip around the same and a separate hooded cover of metal, having shoulders around its bottom and an external downward lip surrounding 70 the said lip of said ink-well and secured thereto, so that the tendency to split the ink-well from expansion of the metal cover is avoided; also, in making my self-closing cover circular at the bottom to fit a cylindrical ink- 75 well and tapered and expanded above to form a flat vertical valve-seat in front of the hood, and a transverse apex over the same; also, in the special construction of said hood, enlarged beneath to cover with said open hood 80 the surface of an ink-well and tapered forward and upward from behind to a broad transverse apex in front, in which over the front opening is suspended the rearwardly- 85 swinging valve; also, in forming said hood in a single piece ready for the valve, and in having the pivot which supports the valve project laterally through the side of the hood to enable the same to be readily removed, if necessary, and in a split or slotted tube or metal 90 margin for the glass valve to form a support for the same; in the construction of a self-closing cover with an ink-well having laterally-connected pneumatic reservoir to maintain a uniform level of the ink-surface in said 95 well; in an inkstand having multiple ink-wells therein and a hooded cover elongated to cover the same having openings in front corresponding to said ink-wells, each provided with a self-closing valve; in the construction of a metallic cover for an ink-well having an open front, a bottom adapted to be fitted to said ink-well open beneath, a self-closing valve extended downward within said 100

ink-well, and a sloping bottom beneath said open front leading down to the bottom of said valve, and flanged sides within said open front; in a hollow hood open beneath and in front and having side flanges and downwardly-sloped bottom and swinging valve closing against said flanges and the rear face of said sloped bottom, said valve supported upon pivots over the body of said ink-well and relatively near the middle of the same; in the construction of said side flanges sloped from above downward and backward, so that said valve may rest upon and close the same without special counter-weight, and in the special construction of the various parts, as will be hereinafter shown.

Referring to the drawings, A, Fig. 1, is an inkstand having a cylindrical ink-well, as shown in Fig. 2, and a circular lip A' raised above and surrounding the upper margin of the same.

B represents my self-closing cover, which is provided with a circular base having lips or shoulders B' surrounding the same and overlapping the lip A' of the ink-well. This overlapping shoulder B' is cemented to the base A by plaster-of-paris or other cement interposed between the outer surface of A' and the inner surface of B'. The hood, which carries the self-closing valve D, rises above this circular base, and is tapered forward and upward from the rear, preserving its transverse width, so that at B² it forms a broad transverse apex. From this apex the front is cut away nearly to the bottom or quite down to the circular base of the cover, and at the top of the open front B⁴ is hinged the valve D, which closes against the flanges B⁶ B⁶ along the sides of B⁴, but may be freely pressed backward to the rear. To the rear side of the valve D, within the hollow hood B or above the same, I attach a counter-weight D' to cause the said valve to close; but in Fig. 7 I slope these flanges backward and downward, so that the flat valve D rests by gravity against the same. The valve D is supported by a transverse pivot at its upper part, and these pivots extend laterally through the side wall of the hood, so that the pivot and valve may be readily removed, if desired.

In the opening B⁴, I show a bottom plate B⁵, which is sloped downward and backward, and its free edge joins the lateral flanges B⁶ B⁶, and the valve D closes against all at the same time. I usually place the flanges and the free edge of B⁵ well within the circle of the ink-well, both to enable the straight valve to have room in the circular ink-well and also to give a deep slope to B⁵, to assist the pen in its descent and to enable the valve to rest by its margin in or near to the ink-surface, and the free edge of B⁵ also. This, though not absolutely essential, is a valuable feature of my invention. I prefer to use a heavy non-corrosive cast metal—such as white-metal—for the parts of my hood which come in contact with the more or less acid ink, which I usually re-

tain by gravity alone in place upon the ink-well; but other metal heavily plated with nickel or otherwise protected may be used, 70 cemented to the inkstand.

In Fig. 11 I show an inkstand provided with several ink-wells A³ A³ A³ and a laterally-elongated hood B⁸, having openings to correspond to said ink-wells. The rearwardly-swinging valves 1 2 3 D close these openings and give access to the ink which may differ in color or quality for each. The rod E extends along the apex B² and all the valves are pivoted thereupon. These openings may front 80 in the same or different directions.

In Fig. 10 I show an inkstand, which may be single or multiple, provided with an ink-well C open at the top, upon which rests, and is cemented thereto, if desired, the cover B, having opening B⁴ in front and rearwardly-swinging valve D, the shoulders B' B' serving to secure the said cover B to the top of the ink-well C. From near the bottom of C extends a transverse supply-passage c, which communicates 90 with the bottom of the air-tight reservoir C' on the same level as C, or slightly higher. As the ink-level in C tends to sink below the upper margin of the passage c, a small quantity of air will enter the reservoir C' through said 95 passage, and a corresponding quantity of ink will flow into the ink-well C, raising its level and closing the passage c like a valve, thus maintaining a constant height in the ink of the well C, and this is a matter of importance 100 in my invention, though not essential, as my valve is at a definite height and the pen-holder works best when its passage through the said valve is regulated in required distance, as is done by this device C c C'. 105

I prefer to have the lower part of my valve D and the free edge of the sloped bottom B⁵, as shown in Fig. 1, below the ink-level in the well C, as in this way the pen-holder is not smeared with ink above the pen, as it would 110 be if the valve D were above the top surface of the ink-well; hence I drop the valve D and its bearings, so that the valve swings with its lower margin in the ink-well C below its upper surface, and the free edge of the 115 sloped bottom B⁵ is also correspondingly sunk in the ink-well C. This also prevents sticking of the valve by the gum contained in the ink, and the clogging of the valve or its seat from dried crusts of ink formed thereupon, 120 and reduces the total height upon the table. In order to have this sloped bottom B⁵ extend downward into the ink-well, I usually form my metal cover with its broad apex not over the front of the hood, but part way across the diameter of the ink-well C, and in some cases near its middle, so that a pen presented to the said valve will pass between the sides of the hood through the opening B⁴ and down over the sloped bottom B⁵ for a considerable 125 distance before it strikes the valve, thus insuring a natural descent for the pen-holder, and presenting the pen-point very obliquely 130 to the surface of the valve D; also, if the

valve tends to adhere to the side flanges and the free edge of the sloped bottom B^5 , by reason of the valve and sloping bottom B^5 forming an acute angle with each other, the 5 pen will enter this angle and disengage the valve without injury, while if presented directly to the point of a valve thus struck it would destroy the pen-point.

If the valve be placed above the ink-well 10 entirely, it will be readily seen that the pen will be liable to present too bluntly against the valve, and the ink upon the sides of the valve and the flanges will smear the pen-holder, and when the pen is withdrawn will 15 by the valve riding over the pen-holder strip off a new supply to gum the valve to its seat, to form lumps liable to hold the valve partially open and to smear the pen-holder again in its next presentation. I also prefer to use 20 a valve of glass or other vitreous substance, as broadly claimed in my former Letters Patent aforesaid, since the constant jogging of the point of a steel pen against a valve of metal will roughen its surface and very soon 25 cause the pen-point to catch in these roughnesses and break the nib; also, unless made of a non-corrosive metal, which is mostly soft as well as costly, the ink will rapidly complete the roughening of the valve which the 30 pen-point commences. Perfect smoothness in permanent use is essential to the best working of this valve. In certain cases, as for mucilage-holders, a softer metal may be used; but I prefer to use glass or the like even then. 35 In Fig. 7 I show an ink-well square in cross-section, (see Fig. 8,) and when I make my ink-stand complete as a whole I prefer to use this form; but with ink-wells as used in the market, which are usually cylindrical inside, 40 I show, describe, and claim the circular hooded cover, as shown in Fig. 1, which has certain advantages of cheapness, and allows the cover to be rotated at will, if desired.

In my former Letters Patent I described 45 and claimed a valve of glass or other vitreous substance and showed the same provided with laterally-projecting pins to support the same in open bearings in the cover, which was formed integral with the body of the ink- 50 stand; but such pins are liable to be broken off in use, and my present invention comprises the use of such metallic valve, (see Figs. 3, 4, and 5,) provided with a marginal strip of metal, F , attached to one side of the 55 valve D , and which forms a support for said glass valve not liable to be broken, and easily capable of support in the hood either by the metal projecting laterally from the sides of the valve or from a pin E attached to the 60 said metal edge and supported in the sides of the hood.

It will be observed that in all my figures the valve is supported in bearings in the sides of the metal hood at the ends of the transverse apex, and not by a separate hinge within 65 the hood, and attached to the rear side of the cover over the opening B^4 , as in the latter

case the valve cannot be readily removed, and if the hinge be of metal the same is corroded by the acid fumes of the ink and very 70 soon sticks in the hinge and ceases to work. It is essential that the valve-bearings be readily accessible and not confined within the closed hood, but be exposed to the atmosphere either from the ends, the front, or above, and 75 preferably from all three directions.

In Fig. 7 I show a solid metal valve pierced at its upper margin, and the pin E is inserted from without through the side of the hood, and thence through the valve and into a socket 80 in the opposite side. The pin E being removed, the valve D will readily drop out, and may be replaced with another or cleaned and again inserted.

The metallic bearing which I prefer to use 85 with my glass valve and the glass valve itself are as follows: The valve D , Figs. 3, 4, and 5, is preferably rectangular in form, the depth being greater than the width and the lower margin bent backward to prevent engagement 90 with any projection upon a pen or pen-holder, and also to serve as a counter-weight to assist in closing the valve. This counter-weight may be placed at any part of the valve, or, as stated in my former Letters Patent aforesaid, 95 may be above the pivoted support of the valve and above the hood itself, extending backward over the same and attached by a bent extension to the valve itself.

In Fig. 7 I do not use any special counter-weight, but incline my flat valve downward and backward, which enables it to rest closed in a sloped position and adds to the acuteness of the angle formed with the sloping bottom B^5 , and also prevents liability of catching upon 105 the edge thereof (which is rounded) of the pen or pen-holder. The upper part of the glass valve is preferably rounded along the top edge, and near the margin is a transverse groove d from side to side, and on the opposite 110 side a similar groove, or a short groove in the center only. I prefer to make the short groove d' a little lower than the opposite groove d to prevent weakening of the valve, and also to throw the slotted tube F farther around and 115 flatten the bearing on the front side, which is the one occupied by the groove d . The upper margin of the valve D is also enlarged somewhat, and the grooves d and d' occupy this enlarged part D^2 . F is a tube of spring 120 metal, preferably spring-brass nickel-plated, and I usually use a piece of drawn tubing for the purpose, cut to a proper length, and with or without closed ends. This tube is slightly longer than the width of the valve, and may 125 have a diameter of a quarter of an inch. In this tube, leaving the ends cylindrical and entire, I form a longitudinal slot long enough to permit the insertion of the valve-head and of a corresponding width, except in the middle portion, where I form the slot with an inwardly-projecting lip F^2 , which serves as a spring. The head of the valve D being forced into the slot, the free straight edge F^3 will 130

engage in the groove d entirely across the valve, being adapted accurately thereto, and the spring-lip F^2 will seat itself in the groove d' , and by its spring tension draw the free edge F^3 firmly into the groove d , so that the tube cannot be removed without rotating it upon the head of the valve against the spring F^2 with considerable force, so as to disengage the said lip F^2 from the said groove d . The tube then may be readily pulled off.

While I use the two grooves d and d' for greater security, the spring-lip F^2 may rest against the face of the valve or beneath the swell at the upper margin thereof; but I prefer to use both grooves, as shown. The projecting ends $F' F'$ of the slotted tube F serve as supports for the valve, seated in bearings $B^7 B^7$ of the hood B , which bearings may be open, as shown in Fig. 9, or closed, as shown 20 in Fig. 2.

I do not always use the projecting ends $F' F'$ as valve-supports, but sometimes use a slotted tube F as short as or shorter than the width of the valve and pass a pin transversely 25 through the tube F , supporting it in the sides of the hood, as shown in Figs. 3 and 11. The valve shown in Fig. 7 is preferably of metal with a fire-glazed or enameled surface of vitreous material; but sometimes a hard metal 30 may be used for cheapness, but is not to be depended upon for permanent use. A spring may be used to assist in closing the valve; but this also cannot be depended upon, and a counter-weight or sloped valve is in every 35 way preferable.

At D^3 , Fig. 3, I show my valve D provided with a notch in its lower margin, so that when used as a self-closing cover for a mucilage-stand or the like the handle of the brush 40 may be allowed to project through this notch when the valve is closed, and the sides of the said notch will serve as a convenient stripper for the surplus mucilage upon the brush. A mucilage-holder like Fig. 10 is very useful 45 with my invention.

I do not rigidly confine myself to the specific construction herein shown and described, but vary the same to suit special requirements, such as would be suggested by a mechanician skilled in the art, without departing from the principles of my invention, as herein shown, described, and claimed.

Having now described my invention, what I claim, and desire to secure by Letters Patent, 55 is—

1. As an article of manufacture, a self-closing cover for ink-wells, consisting of the hollow metal hood B , open beneath and adapted to be attached to the margin of an ink-well, 60 having flanged opening B^4 in front and a pivoted valve D , adapted to close from the rear within said hood against the flanged sides of said opening B^4 , said valve supported in bearings in the sides of said hood B , substantially as described.

2. As an article of manufacture, the hollow metal hood B , expanded and open beneath to

cover an ink-well, and tapered above to form a transverse apex with a sloped rear side, said hood vertically open in front, and a rear-wardly-swinging valve pivoted to the upper margin of said opening B^4 , said opening having flanged sides, and said valve adapted to be swung back against said sloped rear side of said cover and to close against said flanges $B^6 B^6$ by a counter-weight attached thereto, and said hood B having external overlapping shoulder B' , adapted to embrace the projecting neck of an ink-well, substantially as described. 70 75 80

3. In combination with inkstand A , having ink-well C , with circular aperture and lip A' , the self-closing cover having circular base with overlapping shoulders $B' B'$, adapted to embrace said lip A' and be cemented or otherwise attached thereto, said cover having central hood B , open beneath and tapered above to a broad transverse valve-seat, and flanged opening B^4 , together with valve D , pivoted to the upper margin of said opening B^4 , closed against flanges $B^6 B^6$ by a counter-weight attached in rear of said valve, and adapted to be swung backward in said hood B by pressure applied to the front thereof and close automatically against said flanges $B^6 B^6$, substantially as described. 85 90 95

4. As an article of manufacture, the hollow hooded cover B , open beneath, having opening B^4 in front, and flanges $B^6 B^6$, shoulders $B' B'$ around the base thereof, the whole formed integral, and the valve D , attached to the upper margin of said opening B^4 , adapted to be swung to the rear in said hood, closed automatically against flanges $B^6 B^6$ by a counter-weight upon said valve D , said valve supported by bearings in the sides of said hood B , the whole adapted to be attached to an ink-well, substantially as and for the purposes described. 100 105

5. In combination with the ink-well C , the hooded cover B , separate therefrom and adapted to be fitted thereto, said hood having open front B^4 opening beneath into said ink-well, flanges $B^6 B^6$, and rearwardly-swinging pivoted valve D , supported above said opening B^4 , adapted to close against said flanges $B^6 B^6$, said valve extended downward below the lower margin of hood B and adapted to be swung to the rear within said ink-well, substantially as and for the purposes described. 110 115 120

6. In combination with the inkstand A , having ink-well C , the separate metal cover having shoulders $B' B'$ to support the said cover upon the margins of said ink-well, hollow hood B , open into said ink-well, having opening B^4 and flanges $B^6 B^6$, transverse bottom part B^5 of said opening B^4 , sloped downward and backward into the concavity of said ink-well, the free edge thereof continuous with said flanges $B^6 B^6$, together with rearwardly-swinging valve D , adapted to close automatically against said flanges $B^6 B^6$ and the free edge of said bottom B^5 , said valve D 125 130 135

- hung with its lower part within the concavity of said ink-well and forming with the sloped surface B^5 an acute angle, substantially as described.
- 5 7. As an article of manufacture, a self-closing cover for inkstands, consisting of the hollow hood B , cast in a single piece, except the valve, of white-metal or other material unaffected by the acids of ink, open and expanded beneath, having shoulders $B' B'$, adapted to support the same upon the margins of an inkwell, tapered above to a transversely-flat apex, said cover having opening B^4 in the front thereof, side flanges $B^6 B^6$ within said opening B^4 , downwardly-sloping extended bottom B^5 , and transversely-pivoted flat valve D , supported along the flattened apex B^2 of said hood in bearings in the sides of said hood B , and adapted to be swung backward within 10 said hollow hood when pressed against from the front through said opening B^4 and to be closed by gravity against said flanges $B^6 B^6$ and the free edge of said sloped bottom B^5 when said pressure has been removed, the 15 whole constructed separately from and independent of said ink-well and adapted to be applied thereto for temporary or permanent use, substantially as described.
8. In combination with the hood B , having 20 self-closing valve D , operated by the insertion or withdrawal of a pen-point through the opening B^4 , the inkstand $A A^2$, having ink-well C , opening vertically above and adapted to support the said hood B upon the marginal 25 surfaces thereof, the lateral supply-reservoir C' , and the small connecting-passage c , connecting the bottom portions of C and C' , said reservoir C' air-tight above and adapted to maintain a uniform level of ink-surface in 30 the said ink-well C , substantially as and for the purposes herein shown and described.
9. In combination with the pneumatic ink-supplying reservoir C' , an open ink-well C and connecting-passage c , the hood B , covering 35 said ink-well C and supported by the margins thereof, said hood having supporting-shoulders $B' B'$, opening B^4 in front thereof, flanged sides $B^6 B^6$, and sloping bottom B^5 , together with rearwardly-swinging valve D , 40 pivoted at its upper margin to the apex B^2 of said hood B , and adapted to close automatically against said flanges $B^6 B^6$ and said sloped bottom B^5 and close said opening B^4 , substantially as described.
- 50 10. An inkstand having a pneumatic ink-supplying reservoir C' , open vertical ink-well C , and passage c , connecting the lower parts of C and C' , in combination with a self-closing valve and cover $B D$, fixed at a definite 55 height above the ink-surface of said ink-well C , said ink-level made constant in said ink-well by automatic supply from said reservoir C' through said passage c , substantially as described.
- 60 11. In combination with the hollow hood B , expanded and open beneath, tapered and transversely flattened to an apex B^2 , adapted 65 to be applied to and supported by the margins of an open ink-well C , and provided with opening B^4 in the front of said hood, the flanges $B^6 B^6$ along the sides of B^4 , said flanges inclined to the rear from above downward, and the self-closing valve D , pivoted at E transversely along the said apex, and adapted to rest by gravity in an inclined position 70 against the said sloped flanges $B^6 B^6$ and close the said opening B^4 , substantially as described.
12. In combination with the glass valve D , the slotted metal tube F , adapted to embrace the free upper margin of said valve, said valve securely fixed therein, the free ends $F' F'$ of said tube F , cylindrical in cross-section and projecting laterally from the sides of said valve, adapted to form supports for 80 the same, and the bearings $B' B'$ in hood B , substantially as described.
13. In a self-closing ink-well cover, the valve D , of glass or the like, having transverse grooves $d d'$ near the margin and on 85 opposite faces thereof, in combination with the slotted metal tube F , having opposite edges $F^2 F^3$ along said slot adapted to engage with said grooves $d d'$ and securely hold said valve in place in said slotted metal tube and 90 form a metallic support for the same, substantially as described.
14. In combination with the valve D , having transverse grooves $d d'$ on opposite faces and near one of the free edges thereof, the 95 slotted tube F , adapted to support the said valve in bearings, having edge F^3 along said slot adapted to engage with groove d entirely across said valve, and the spring-lip F^2 , projecting from the middle of the opposite edge 100 of said slot, said spring-lip adapted to engage with said groove d' and by its spring tension force the opposite edge F^3 into groove d and 105 securely hold the said slotted tube F in place upon said valve D , substantially as described. 110
15. In a self-closing inkstand-cover, in combination with the glass valve D , transversely grooved at d and d' upon opposite faces, the slotted spring-metal clamping-tube F , adapted to embrace the free margin of said valve and 115 engage along the edge of said slot with one of said grooves and prevent displacement thereof, together with pivoted valve-supports attached to said slotted tube and pivoted in said cover B , substantially as described. 120
16. In combination with a flat glass valve having a transverse groove near its margin, a slotted spring-metal tube adapted to engage by one of the edges of said slot in said groove to prevent displacement thereof, and held in 125 place by the pressure of the opposite edge of said slot against the opposite face of said valve, said slotted tube adapted to form a metal support for said valve and to be supported in bearings to allow motion of said valve thereupon, substantially as and for the purposes herein shown and described.
17. In combination with the hollow hood B , open beneath and adapted to be supported

- upon the margins of the open well C and form a cover for the same, said hood having opening B⁴ in front, a self-closing valve pivoted at its upper margin within said hood,
- 5 adapted to swing to the rear upon said pivot by pressure applied to the front of said valve and close automatically against flanged sides B⁶ B⁶ of opening B⁴ when said pressure has been removed, said valve having a notch D³
- 10 in its lower margin, adapted to give room for and permit withdrawal of a mucilage-brush or the like from said well C when said valve is closed, substantially as described.
18. In a self-closing ink-well cover B, the hollow metal hood open beneath into the ink-well C, and having opening B⁴ in front provided with flanged sides B⁶ B⁶, said hood expanded beneath, flattened and brought to a broad transverse apex above, said cover B
- 20 extended to said apex B² and closed behind, in combination with a rearwardly-swinging valve D, supported in bearings in the sides of said cover B, and adapted to close from the rear against said flanged sides B⁶ B⁶, said
- 25 valve D elongated from above downward and having its lower edge D' bent backward, said edge D' adapted to be swung to and fro beneath the surface of the ink in said ink-well C, and close against the rear side of the flanges B⁶ B⁶ and the rear edge of sloped bottom B⁵ of open front B⁴, said rear edge extended down within said ink-well into or near the surface of the ink therein, substantially as and for the purposes described.
- 35 19. As an article of manufacture, a heavy cast white-metal cover B, provided with conical flattened hood open beneath, and open

front, and having valve D supported therein, and shoulders B' B', the whole adapted to rest by its own weight upon ink-well C, substantially as described.

20. In combination with the inkstand A, having a vertically-sunk ink-well C in the upper face thereof, the hollow hooded cast-metal cover B, extended over said ink-space, 45 having shoulders B' B', adapted to rest by gravity upon the sides of said ink-well open beneath, and having flanged opening B⁴ in front, said opening vertical or inclined and in rear of the front margin of said ink-well 50 opening, and sloped bottom B⁵, extending downward and backward from the front of said opening B⁴, the rear edge thereof continuous with said flanged sides B⁶ B⁶, together with a valve supported above said opening 55 B⁴, extending downward into said ink-well C, adapted to close by a counter-weight attached to the rear side thereof against said flanges B⁶ B⁶ and said free lower edge of said sloped bottom B⁵, the whole constructed substantially as and for the purposes herein shown and described.

21. In a self-closing inkstand-cover having hood B open beneath and opening B⁴ in front of said hood, the glass valve D, in combination with a metallic strip attached to one margin thereof and adapted to form a pivot or support for the same, substantially as described.

ISAAC W. HEYSINGER.
